W. C. BALKE.
CLOSURE FASTENING.
APPLICATION FILED SEPT. 13, 1915.

1,199,753.

Patented Oct. 3, 1916.

UNITED STATES PATENT OFFICE.

WILLIAM C. BALKE, OF LOUISVILLE, KENTUCKY.

CLOSURE-FASTENING.

1,199,753.

Specification of Letters Patent.

Patented Oct. 3, 1916.

Application filed September 13, 1915. Serial No. 50,439.

To all whom it may concern:

Be it known that I, WILLIAM C. BALKE, a citizen of the United States, residing at Louisville, in the county of Jefferson and State of Kentucky, have invented certain new and useful Improvements in Closure-Fastenings, of which the following is a specification.

The primary purpose of the present invention is the provision of novel and unique fastening means for doors, covers and closures of every description whereby the same when in closed position may be made secure against opening from the outside.

While the invention is particularly designed for securing covers of coal chutes and openings in vaults it is to be understood that the same may be applied to closures of any kind associated with metal frames fitted into the opening to be protected or covered by means of the closure to which the novel fastening means are applied.

The invention consists in the improved construction and novel arrangement and combination of parts which will be herein-after fully described and particularly claimed.

In the accompanying drawings has been illustrated a simple and preferred form of the invention, it being however, understood that no limitation is necessarily made to the precise structural details therein exhibited, but that changes, alterations and modifications within the scope of the invention as claimed may be resorted to when desired.

Referring to the drawings, Figure 1 is a central section of a closure and frame provided with fastening means embodying the invention; Fig. 2 is a detail view of a portion of the closure as seen from the under side; Fig. 3 is a detail perspective view of the latch.

Corresponding and like parts are referred to in the following description and indicated in all the views of the drawings by the same reference characters.

In Figs. 1 and 2 the numeral 1 designates a lid, cover or closure and 2 a frame therefor, the same being particularly designed for coal chutes or openings in vaults and kindred underground structures. The frame 2 may be of any of the usual styles provided with an outwardly extending flange. This flange may be located at or near the upper edge of the frame, as indicated at 3, or may be disposed at or near the lower edge of the frame,

as indicated at 4. The style and construction of the frame are immaterial within the purview of the invention which resides in the fastening means. A gravity latch has pivotal or rocking connection with the closure 1 and is adapted to engage a stop of the frame 2. In the preferable arrangement the type of closure 1 is provided with two gravity latches which have a diametric arrangement so as to engage the frame 2 at opposite points. A detail description of one of the fastening means will suffice for a clear understanding of both.

The frame 2 is formed with a lug 5 constituting a stop to be engaged by the active end of the latch. The stop 5 is approximately of hook-shape or overhanging form so as to make firm engagement with the engaging portion of the latch which is likewise of hook-shape. The latch comprises a shank 6, a hook 7, a cross head or lateral journals 8, an arm 9 and a lift-piece 10, the several parts being of integral formation. The cross head 8 is disposed at one end of the shank 6 and projects laterally from both sides thereof to form the journals or axis about which the latch turns. The hook-shaped engaging end 7 is disposed at the opposite end of the shank and is arranged to engage the hook-shaped stop or overhanging lug 5. The arm 9 projects from the shank in an opposite direction to the hook-shaped portion 7 and the lift-piece or member 10 is arranged at the outer end of the arm 9 and at a slight inclination thereto. The lift-piece 10 and arm 9 being disposed to one side of the shank act by gravitational action to hold the hook 7 in engagement with the stop 5. The ends of the cross head 8 projecting beyond the sides of the shank 6 are made rounding to form journals about which the latch turns.

The closure 1 is formed at its outer edge with a depending rim 11 and at opposite points with recesses in which are fitted the latches. A U-shaped rib 12 is formed upon the inner or underside of the closure 1 and incloses the space in which the latch is pivoted. The inner wall of the rib 12 is undercut so as to retain a filling 13 in place. The side members of the U-shaped rib 12 join the depending rim 11. Wings 14 are formed at the outer ends of the side members of the U-shaped rib 12 and are disposed to underlap the projecting ends of the cross head 8 whereby said ends or journals are

seated on the flange 11 between the wings and the rib 12. The shank of the latch extends between the wings 14. The filling 13 preferably consists of lead or like readily fusible metal which is poured into the space after the latch has been placed in position, thereby preventing displacement of the latch and holding the same in place. When pouring the filling into the recess the closure 1 is placed in horizontal position with the side having the flange or rim 11 and ribs 12 uppermost. After the latches have been placed in position in the recesses with the ends of the cross head 8 beneath the wings 14 the spaces inclosed by the ribs 12 are filled by pouring the molten metal therein.

The frame 2 will generally occupy a horizontal position when in place in the opening of a coal chute or the like. The closure 1 for covering the opening is placed in the frame in the usual way and is made secure by manipulating the latches to cause their hooked ends 7 to engage the stops 5. The latches normally occupy the position substantially as indicated in Fig. 1. When it is required to remove the closure the weighted end or lift member of one of the latches is moved upward, thereby effecting disengagement of the hooked end of such latch from the stop 5. The remaining latch will automatically disengage itself from the stops, as will be readily understood.

When the latches pivot freely the closure may be dropped into position and the latches will automatically engage the stops 5. However, when it is desired to release the closure it is necessary to manipulate one or more of the latches from below, hence the closure may not be released or removed from above. In the event of the closure being provided with an opening, as 15, for the introduction of a pry to assist materially in removing the cover, a guard 16 is located opposite such opening on the under side of the cover to prevent release of the latches by the introduction of a rod or other device through the opening 15.

While the invention is intended chiefly for coal chutes it is equally adapted for cellular doors. When the closure occupies an approximately vertical position it is usually necessary to operate both latches when securing or releasing the door. When the closure is arranged in horizontal position it

may be released by manipulating one of the latches only and pushing upward upon one side of the door, the latch upon the opposite side automatically releasing to admit of removal of the door.

Having thus described the invention, what is claimed as new is:

1. The combination of a closure having a seat on its inner side and wings in front of the said seat, a frame having an overhanging lug adapted to project in advance of 65 said seat, a latch adapted to rock on the said seat and engage said lug, said latch being provided with lateral journals engaging behind the said wings and having a lift member at its free end extending away from 70 the overhanging lug on the frame, and means to retain the latch in operative connection with the closure.

2. A closure having a U-shaped rib on its inner side, wings on the closure in front of 75 said rib, a frame having a lug thereon arranged to project in advance of the rib on the closure, a latch having lateral journals to engage behind the wings and under the rib on the closure, said latch being adapted 80 at its free end to engage the lug on the frame and having a curved arm extending from said free end adapted to fit over the rib on the closure when the latch is released and further provided with a lifting member 85 projecting away from the said arm.

3. In combination with a member formed with a recess, a latch pivotally mounted in the recess, and a filling between the side of the recess and pivotal portion of the latch 90 for holding the latch in position.

4. In combination with a member formed with a recess and having inwardly extending wings at opposite sides of the recess, a latch having pivotal journals engaging under the wings of the recess, and a filling for retaining the latch in position. 95

5. In combination with a member having a recess, the walls of which are undercut and having opposed wings at opposite sides of the recess, a latch formed with opposed journals entering the recess and engaging under the said wings, and a filling for the recess engaging the latch and retaining the same in place. 100

In testimony whereof I affix my signature.

WILLIAM C. BALKE. [L.S.]
